U.S. Cl. D65—1 R

FIG. 1

FIG. 2

FIG. 1 is a front perspective view of a pump;

FIG. 2 is a front perspective view of the structure shown in FIG. 1, but taken from a plane below the base plane of the pump design;

FIG. 3 is a rear elevational view; and

FIG. 4 is a side elevational view.

The base of the structure is a flat planar surface, as is apparent from FIG. 2.

The present application is a continuation-in-part of co-pending application Ser. No. D. 195,064, filed Nov. 2, 1971, entitled "Pump," now abandoned, and assigned to the same assignee as the present application.

We claim:

The ornamental design for a pump, substantially as shown and described.
